United States Patent Office

Des. 188,817
Patented Sept. 13, 1960

188,817

BOTTLE

Jack A. Northrup, Whittier, William D. Rhodes, Long Beach, and Alfred D. Sterges, Los Angeles, Calif., assignors to Purex Corporation, Ltd., South Gate, Calif., a corporation of California

Filed Jan. 4, 1960, Ser. No. 58,893

Term of patent 14 years

(Cl. D58—8)

Fig. 1 is a side elevational view of a bottle embodying our new design, the side not shown being the same as the side shown;

Fig. 2 is a top plan view thereof;

Fig. 3 is a bottom plan view thereof; and

Fig. 4 is a fragmentary cross-sectional view thereof taken on the line 4—4 of Fig. 1.

We claim:

The ornamental design for a bottle, substantially as shown and described.
